UNITED STATES PATENT OFFICE.

NEHEMIAH SLEEPER, OF BURLINGTON, NEW JERSEY, ASSIGNOR TO
SLEEPER, WELLS, AND ALDRICH, OF SAME PLACE.

DESIGN FOR BOTTLES.

Specification forming part of Design No. **6,985**, dated November 4, 1873; application filed September 11, 1873.
[Term of Patent 7 years.]

To all whom it may concern:

Be it known that I, NEHEMIAH SLEEPER, of Burlington, New Jersey, have invented a Design for a Bottle, of which the following is a specification:

My design for a bottle is fully represented in and by the accompanying drawing.

The neck *a* of the bottle terminates at the top in a flange, *b*, and below meets the body *A* with a slight curve, at *x*, from which point the body is expanded abruptly, the part *y*, which is largest in diameter, being rounded, as shown, and from this rounded portion the body is

gradually contracted to the base, so as to assume the form of an inverted frustum of a cone.

I claim—

The design for a bottle, as described and as shown in and by the accompanying drawing.

In testimony whereof I have signed my name to this specification in the presence of two subscribing witnesses.

NEHEMIAH SLEEPER.

Witnesses:

HUBERT HOWSON,
HARRY SMITH.
